UNITED STATES PATENT OFFICE.

OTTO W. SIEBERT, OF WEST GARDNER, MASSACHUSETTS, ASSIGNOR
TO BAY STATE METAL WHEEL COMPANY, OF EAST TEMPLETON;
MASSACHUSETTS.

DESIGN FOR A PROPELLING-FRAME FOR CHILDREN'S CARRIAGES.

SPECIFICATION forming part of Design No. 34,933, dated August 13, 1901.

Application filed June 17, 1901. Serial No. 64,959. Term of patent 14 years.

To all whom it may concern:

Be it known that I, OTTO W. SIEBERT, of West Gardner, in the county of Worcester and State of Massachusetts, have invented and produced a new and original Design for a Propelling-Frame for Children's Carriages and Go-Carts, of which the following is a specification, reference being had to the accompanying drawing, forming a part thereof.

Said drawing represents a perspective view of a propelling-frame, showing my new design.

The leading or material feature of my design consists in the thin continuations *a a* of the push-bars *b b*, the said bars having the upward curves 1 and downward curves 2 and straight lower end portions 3, and the said continuations forming extensions having a length nearly equal to the curved portions of the push-bars and having reverse curves 4

and 5, each of which is of a length substantially equal to the curves in the push-bars, but less abrupt than the latter, the whole producing a wavy or serpentine effect by a plurality of reverse curves of substantially equal length from end to end of the propelling-frame. The extensions *a a* extend from the rear to the front axle of a child's carriage, the bars *b b* extending rearwardly and upwardly from the rear axle. 30

I claim—

The design for a propelling-frame for children's carriages substantially as shown and described.

In testimony whereof I have affixed my signature in presence of two witnesses. 35

OTTO W. SIEBERT.
